UNITED STATES PATENT OFFICE.

RODERICK D. COLEMAN, OF GREENWOOD, VIRGINIA.

HAT-PIN PROTECTOR.

1,073,959.

Specification of Letters Patent. Patented Sept. 23, 1913.

Application filed May 14, 1912. Serial No. 697,217.

To all whom it may concern:

Be it known that I, RODERICK D. COLEMAN, a citizen of the United States, residing at Greenwood, in the county of Albemarle 5 and State of Virginia, have invented new and useful Improvements in Hat-Pin Protectors, of which the following is a specification.

The general object of this invention is 10 the provision of a protector for the point of hat pins, said protector being constructed in a simple manner to form a guard for the point of the pin after the latter has been inserted thereinto, whereby the danger of injuring a person is obviated.

In carrying out the objects of the invention, generally stated above, it will be understood, of course, that the essential features thereof are susceptible to changes in 20 details and structural arrangements, one preferred and practical embodiment being shown in the accompanying drawing, wherein:—

Figure 1 is a plan view of the protector 25 showing a hat pin applied thereto. Fig. 2 is an edge elevation thereof. Fig. 3 is a section on the line 3—3 of Fig. 1.

Referring more particularly to the accompanying drawing in which like reference 30 characters designate similar parts, it will be seen that the invention comprises a single strip of metal consisting of an elongated body 5 having one end 6 thereof bent to form approximately an angle of 45° thereto, said 35 bent end being provided with an aperture 7 for the reception of a hat pin.

The body 5 is bent upon itself adjacent its other end to provide a substantially U-shaped guard portion 8 against which the 40 point of the pin 9 is adapted to abut when said pin is inserted into the protector. The free extremity of the guard portion 8 is bent inwardly at substantially right angles to the body 5 to form an extension 10 which 45 is provided with a laterally extending slot 11. One portion of the extension 10 is adapted to engage the body 5 while the portion on the opposite side of the slot 11 is reduced and rounded as indicated at 12 to

provide a guiding edge which is adapted to 50 guide the pin 9 into the said slot 11 whereby said pin will be prevented from moving laterally in the protector and bind in the opening 7. The portions 5, 6 and 10 are preferably of reduced thickness as compared 55 with the portions 13 and 14 whereby the resiliency of the parts is insured while substantially reinforcing those portions in which independent movement is not required.

From the foregoing description taken in connection with the accompanying drawing, it will be obvious that the invention contemplates providing a hat pin protector which is simple in construction thus reducing 65 the cost of manufacture of the same to a minimum and which is durable and effective in carrying out the purpose for which it is designed.

What is claimed is:—

A hat pin protector constructed of a single length of spring material formed at one end in return bend and having the free terminal of such return bend portion projected toward and into contact with the main 75 length of the strip to form a housing, said laterally projected portion being formed with a slot extending at right angles to the main length of the strip and communicating in a channel opening through one edge of 80 the laterally projected portion with its upper wall inclining upwardly and outwardly from its juncture with the slot, the main length of the strip at a point in advance of the housing being reduced in thickness to 85 provide a resilient section the free terminal of said section being bent upwardly at an angle of approximately 45° to the main length of the strip and formed with an aperture approximately in alignment longitudinally of the strip with the slot in the laterally projected portion.

In testimony whereof I affix my signature in presence of two witnesses.

RODERICK D. COLEMAN.
